UNITED STATES PATENT OFFICE.

HECTOR TOOPS AND CLINTON TOOPS, OF JEFFERSON, INDIANA.

IMPROVEMENT IN HAY-ELEVATORS.

Specification forming part of Letters Patent No. 177,175, dated May 9, 1876; application filed April 18, 1876.

To all whom it may concern:

Be it known that we, HECTOR TOOPS and CLINTON TOOPS, of Jefferson, in the county of Clinton and State of Indiana, have invented a new and Improved Hay-Elevator, of which the following is a specification:

Our invention consists of a hook or claw-lever contrived with the carriage from which the hoisting-fork descends, and with the hoisting-ropes, and a stop-piece against which said hook-lever strikes when the carriage runs out to the place of taking the load, so that it hooks under the head of and engages the hoisting-fork, to hold it while running in the barn with the load and out again, and disengages it at the moment the truck comes out to the hoisting-place, all as hereinafter described.

Figures 1 and 2 are sectional elevations of our improved apparatus, taken on line $\alpha\alpha$ of Fig. 2, the one showing the hoisting-fork down in the position for taking the load, and the other showing it in the position for being carried into the barn; and Fig. 3 is a top view.

A is the truck or carriage, which runs on the rails B, and has the hoisting-fork C suspended from it by the rope D, said rope being connected to the carriage at one end by passing over the bar D' and attaching to the upper end of the claw-lever F. This rope then passes under the pulley G in the hoist-

ing fork, up over the pulley H on the carriage, and thence along through the barn, and over guide-pulleys I, to the place for attaching the power for raising the hay and drawing it into the barn. J is a latch, which catches at K, to hold the truck A while the hay is being elevated, and L is the stop-piece for detaching the elevating-fork when it arrives back to the place for descending. When the head O of the elevator-fork comes up under the latch J it detaches the truck, so that the rope D pulls it into the barn, and as soon as it starts, so as to release the claw-lever F, the rope D swings the claw at the lower head forward under the head of the elevating-fork, to hold it until it has carried its load in and comes back again to the place for descending for another load, when the stop L trips it and lets the fork down. P is the tripping-rope.

Having thus described our invention, what we claim as new, and desire to secure by Letters Patent, is—

The claw-lever F and stop piece L, combined with the headed elevator-fork C, carriage A, and the latch J, substantially as specified.

HECTOR TOOPS.
CLINTON TOOPS.
